(57) **CLAIM**

The ornamental design for an illuminated control device, as
shown and described.

DESCRIPTION

FIG. 1 is a front perspective view showing a first state of an
illuminated control device showing our new design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is a front perspective view showing a second state
thereof;

FIG. 8 is a front view thereof;

FIG. 9 is a left side view thereof;

FIG. 10 is a right side view thereof;

FIG. 11 is a top view thereof;

FIG. 12 is a bottom view thereof;

FIG. 13 is a front perspective view showing a third state
thereof;

FIG. 14 is a front view thereof;

FIG. 15 is a left side view thereof;

FIG. 16 is a right side view thereof;

FIG. 17 is a top view thereof;

FIG. 18 is a bottom view thereof;

FIG. 19 is a front perspective view showing a fourth state
thereof;

FIG. 20 is a front view thereof;

FIG. 21 is a left side view thereof;

FIG. 22 is a right side view thereof;

FIG. 23 is a top view thereof;

FIG. 24 is a bottom view thereof;

FIG. 25 is a front perspective view showing a fifth state
thereof;

FIG. 26 is a front view thereof;

FIG. 27 is a left side view thereof;

FIG. 28 is a right side view thereof;

FIG. 29 is a top view thereof;

FIG. 30 is a bottom view thereof;

(Continued)

FIG. 31 is a front perspective view showing a sixth state thereof;
 FIG. 32 is a front view thereof;
 FIG. 33 is a left side view thereof;
 FIG. 34 is a right side view thereof;
 FIG. 35 is a top view thereof;
 FIG. 36 is a bottom view thereof;
 FIG. 37 is a front perspective view showing a seventh state thereof;
 FIG. 38 is a front view thereof;
 FIG. 39 is a left side view thereof;
 FIG. 40 is a right side view thereof;
 FIG. 41 is a top view thereof; and,
 FIG. 42 is a bottom view thereof.

The gray shaded elements depict illumination.
 The dashed broken lines illustrate structure or features which form no part of the claimed design.
 The dot-dash broken lines illustrate boundaries which form no part of the claimed design.
